United States Patent Office

Des. 182,930
Patented May 27, 1958

182,930

PERFUME BOTTLE

Elsa Schiaparelli, Paris, France

Application September 18, 1957, Serial No. 47,775

Term of patent 14 years

(Cl. D58—8)

Fig. 1 is a front elevational view of a perfume bottle, showing my new design;

Fig. 2 is a side elevational view thereof taken 90 degrees counterclockwise from Fig. 1; and

Fig. 3 is a front perspective view thereof.

I claim:

The ornamental design for a perfume bottle, substantially as shown.
